tion of Ohio

Application April 23, 1953, Serial No. 350,721

4 Claims. (Cl. 137—625.4)

This invention relates to valves in general and more particularly to a throw-over valve for use in liquefied petroleum gas systems.

In isolated fuel supply systems gas such as liquefied petroleum gas is supplied for domestic use from containers which store the gas under pressure, one container being used as a service cylinder while the other is used as a reserve or stand-by cylinder. When the pressure within the service cylinder is depleted and pressure drops below the pressure necessary for the system, a valve must be operated which changes the source of supply to the reserve cylinder. Since the consumer in such installations is normally inexperienced it is necessary that the operation of changing from the supply cylinder to the reserve cylinder be simplified as much as possible. Also, since the fluid being controlled in such a system is inflammable, it is essential that the throw-over valve be essentially foolproof so as to prevent any possibility of explosion or fire.

It is an important object of this invention to provide a throw-over valve for switching from one source of fluid under pressure to another source of fluid under pressure which is easy to operate and relatively foolproof.

It is another object of this invention to provide a throw-over valve for use in liquefied petroleum gas installations which virtually eliminates possibility of leakage or contamination of the gas within the system which might cause fire hazards.

It is still another object of this invention to provide a throw-over valve wherein the tolerances of manufacture are relatively large so that the fabrication cost is reduced to a minimum.

The foregoing and other objects and advantages will become apparent in view of the following description taken in conjunction with the drawings, wherein:

Fig. 1 is a side view partially in section showing a manual throw-over valve embodying a preferred structure according to this invention;

Fig. 2 is a cross sectional view taken along 2—2 of Fig. 1; and,

Fig. 3 is a cross sectional view taken along 3—3 of Fig. 2.

In a preferred embodiment of this invention the throw-over valve is provided with a body formed with a central bore terminating in an end wall. A plurality of inlets are formed in the body having inlet passages opening into said end wall providing a plurality of inlets into the central bore. An outlet is also formed in the body opening into the central bore. A resilient disc is positioned against the end wall overlapping the inlet passages. A rigid ball is positioned within the central bore and adapted to engage the resilient disc and urge that portion of the disc engaged by the ball toward the end wall

2

of the central bore. Drive means are provided to move the ball from a position adjacent to one of the inlet passages to a position adjacent to the other inlet passage and to urge the ball into engagement with the resilient disc thereby causing the disc to seal at least one of the inlet passages and isolate it from the central bore.

Referring to the drawings, the body 10 is formed with a bore 11 terminating in a substantially radial end wall 12 at the inner end thereof. The body 10 is also provided with inlets 13 and 14 which are preferably threaded so they may be attached to sources of fluid under pressure by any normal coupling means. In the preferred embodiment of this invention the inlets 13 and 14 are coaxial.

Smaller bores 16 and 17 coaxial with the inlets 13 and 14 project beyond the bottom of the inlets 13 and 14 and are terminated at a point spaced from each other by the wall 18. Inlet passages 19 and 21 extend between the end wall 12 and the bores 16 and 17 respectively providing fluid communication between the inlets 13 and 14 and the bore 11 through the bores 16 and 17.

In the preferred embodiment of this invention the inlet passages 19 and 21 are formed with axes parallel to and equally spaced from the axis of the bore 11. An outlet 22 is provided in the body 10 which is in fluid communication with the bore 11 through the outlet passages 23 and 24 at a point spaced from the end wall 12. The outlet 22 is also formed with threads to facilitate the coupling with the system to be supplied with the fluid under pressure.

The bore 11 is formed with the threads 26 at its outer end into which the bonnet 27 may be threaded. The bonnet 27 is formed with a central bore 28 therethrough adapted to guide the cam assembly 29.

The cam assembly 29 embodies a cam member 31, a cap or handle 32, a spherical sealing ball 33 and a resilient spring 34. The cam member 31 is formed with a shaft section 36 adapted to extend through the bore 28 in the bonnet 27 thereby providing a guide for the cam assembly 29.

A resilient disc 37 which is preferably formed of synthetic rubber is positioned against the end wall 12 of the bore 11 and is adapted to overlap the inlet passages 19 and 21. The spherical sealing ball 33 which has a diameter substantially larger than the diameter of the inlets 19 and 21 engages the other side of the disc 37 and urges the disc into engagement with the portion of the end wall 12 adjacent to the ball 33 under the force of the spring 34. The cam 31 is provided with an offset bore 38 having a diameter larger than the diameter of the sealing ball 33 in which the sealing ball 33 is positioned. The spring 34 extends between the bottom 39 of the offset bore 38 and the sealing ball 33 thereby urging the sealing ball into tight engagement with the disc 37. The axis of the offset bore 38 is preferably parallel to the axis of the bore 11 and spaced therefrom a distance equal to the spacing of the axes of the inlet passages 19 and 21 from the axis of the bore 11. Because the spacing of the offset bore 38 is equal to the radial spacing of the inlet passages 19 and 21 rotation of the cam assembly 29 will position the sealing ball 33 adjacent to the opening of one of the inlet passages 19 and 21 in the end wall 12 thereby causing the sealing ball 33 to urge the disc 37 into tight sealing engagement with the opening of the adjacent inlet passage 19 or 21 thereby isolating this inlet from the bore 11.

The cam 31 is formed with a shoulder 41 adjacent to the end of the shaft section 36 which provides a surface against which the thrust bearing 42 is urged. In the preferred embodiment, the thrust bearing is formed of nylon or similar material which has desirable wearing characteristics. Positioned between the thrust bearing 42 and the end face 43 of the bonnet 27 is a shaft seal 44 of the O-ring variety which is adapted to engage the shaft section 36 and the end face 43 of the bonnet 27 thereby providing a fluid seal therebetween.

The outer end of the shaft section 36 is formed with a flat 46 which is adapted to engage a similar flat in the recess 47 formed in the handle 32 thereby preventing a relative rotational movement between the cam 31 and the handle 32. A screw 48 is provided to securely fasten the handle 32 to the cam member 31.

The cam member 31 is formed with a stop surface 49 adapted to engage the stop member 51 which is secured in the bore 52 in the body 10. In the preferred embodiment the stop 51 is adapted to engage and limit the rotation of the cam member 31 when the sealing ball 33 is positioned adjacent to one or the other of the inlet passages 19 or 21.

In operation the supply cylinder and the reserve cylinder are each connected to one of the inlets 13 or 14 and the system to be supplied is connected to the outlet 22. If the cam assembly 29 is in the position shown in Fig. 2 fluid under pressure entering the inlet 13 flows through the bore 16 and the inlet passage 19 deflecting the disc 37. From the inlet passage 19 the fluid flows into the bore 11 and out through the outlet 22 to the system to be supplied. The source of fluid under pressure connected to the inlet 14 is isolated from the bore 11 by the disc 37 which is pressed into sealing engagement with the opening of the inlet passage 21 by the sealing ball 33. When the supply of fluid under pressure connected to the inlet 13 is exhausted the cam assembly 29 is rotated until the sealing ball 33 is positioned adjacent to the inlet 19 thereby providing fluid communication between the inlet 21 and the bore 11. At this time the exhausted cylinder which is connected to the inlet 13 may be removed and a new cylinder installed at this inlet.

By providing the bore 38 with a diameter larger than the diameter of the ball a good seal of the inlet is insured even if the bore 38 is not exactly coaxial with the inlet opening being sealed. Reference to Fig. 2 will disclose that the ball 33 will deflect the disc 37 into the inlet opening and automatically align itself relative to the inlet so long as enough clearance is provided between the bore 38 and the ball. Ease and certainty of operation are also characteristic of this valve since the ball tends to roll between its positions and since the resilient disc insures a seal even though the valve seat or the ball might not be perfectly formed.

An added safety factor is provided since the disc 37 is adapted to normally engage the end wall 12 so if the pressure within the pressure source is reduced below the pressure within the system the disc 37 acts as a check valve to prevent any flow of air into the bore 11 and on into the system thereby preventing any possibility of a combustible mixture being present within the system which could cause explosions and fire hazards.

Having completed a detailed description of a preferred embodiment of the present invention so that others skilled in the art may be able to understand and practice the same, I state that what I desire to secure by Letters Patent is not limited by said preferred embodiment but rather is defined in what is claimed.

What is claimed is:

1. A throw-over valve comprising a body formed with a main chamber terminating in an end wall, a plurality of inlet passages in said body opening into said chamber through said end wall, an outlet formed in said body in fluid communication with said chamber in an area spaced

from said end wall, a flexible disc positioned against said end wall covering all of said inlet passages, a ball in said chamber adapted to engage and urge said disc into sealing engagement with at least one of said inlet passages, 5 means for rolling said ball on the side of the disc away from said inlet passages in a path intersecting the center line of said inlet passages and urging said ball against said disc adjacent to at least one of said inlets, said disc being free to be deflected away from the other of said inlet passages by fluid flow through said passages into said chamber.

2. A throw-over valve comprising a body formed with a main chamber terminating in an end wall, a plurality of inlet passages in said body opening into said chamber through said end wall, an outlet formed in said body in fluid communication with said chamber, a resilient disc positioned against said end wall covering all of said inlet passages, a ball in said chamber adapted to engage and urge said disc into sealing engagement with at least one of said inlet passages, drive means for rolling said ball on the side of the disc away from said inlet passages in a path intersecting the center line of said inlet passages to positions adjacent to each of said inlets, and spring means to urge said ball against said disc, said disc remaining substantially non-rotative relative to the wall during the moving of said ball between positions adjacent to each inlet.

3. A throw-over valve comprising a body formed with a main bore terminating in a substantially flat end wall, 30 a plurality of inlet passages with their axes parallel to and equally spaced from the axis of said main bore in said body opening into said chamber through said end wall, an outlet formed in said body in fluid communication with said main bore spaced from said end wall, a resilient disc positioned against said end wall covering all of said inlet passages, a cam mounted in said body for rotation about an axis coaxial with said main bore formed with an offset bore parallel to and spaced from the axis of said main bore a distance substantially equal to the spacing of the axes of said inlet passages from the axis of said main bore, a ball in said offset bore adapted to engage and urge said disc into sealing engagement with at least one of said inlet passages, and spring means to urge said ball against said disc, rotation of said cam rolling said ball on the side of the disc away from said inlet passages in a path intersecting the center line of said inlet passages from a position adjacent to one of said passages to positions adjacent to the other of said passages, said disc remaining substantially non-rotative relative to said end wall during said rolling of said ball.

4. A throw-over valve comprising a body formed with a main bore terminating in a substantially flat end wall, a plurality of inlet passages with their axes parallel to and equally spaced from the axis of said main bore in said body opening into said chamber through said end wall, an outlet formed in said body in fluid communication with said main bore spaced from said end wall, a resilient disc positioned against said end wall covering all of said inlet passages, a cam mounted in said body for rotation about an axis coaxial with said main bore formed with an offset bore parallel to and spaced from the axis of said main bore a distance substantially equal to the spacing of the axes of said inlet passages from the axis of said main bore, a ball in said offset bore adapted to engage and urge said disc into sealing engagement with at least one of said inlet passages, and spring means to urge said ball against said disc, the diameter of said ball being substantially larger than the diameter of said inlet passages and the diameter of said offset bore being substantially larger than the diameter of said ball, rotation of said cam rolling said ball on the side of the disc away from said inlet passages in a path intersecting the center line of said inlet passages from a position adjacent to one of said passages to positions adjacent to

the other of said passages, said disc remaining substantially non-rotative relative to said end wall during said rolling of said ball.
